UNITED STATES PATENT OFFICE.

HUGH SINCLAIR BEATTIE, OF TEZIUTLAN, MEXICO.

EMERGENCY-BRAKE-SETTING DEVICE.

1,042,869.

Specification of Letters Patent. Patented Oct. 29, 1912.

Application filed June 21, 1910. Serial No. 568,132.

To all whom it may concern:

Be it known that I, HUGH SINCLAIR BEATTIE, a citizen of the United States, and a resident of Teziutlan, Puebla, Mexico, have invented a new and Improved Emergency-Brake-Setting Device, of which the following is a full, clear, and exact description.

This invention relates to a new and improved automatic device for setting the brakes on trains equipped with pneumatic brakes, which will operate to set the brakes when the car is subjected to any abnormal jolts or jars, as by the wheels leaving the tracks or by the breakage of one of the wheels of one of the trucks.

An object of this invention is to provide a device which will be simple in construction, inexpensive to manufacture, strong, durable, readily accessible, and both positive and reliable in its operation.

A further object of this invention is to provide a control for the train pipe of an air brake system, which will be operative to automatically open the pipe to the atmosphere when the train on which the pipe is located is subjected to an abnormal jar or jolt.

These and further objects, together with the construction and combination of parts, will be more fully described hereinafter and particularly set forth in the claims.

Reference is to be had to the accompanying drawings forming a part of this specification, in which similar characters of reference indicate corresponding parts in all the views, and in which—

Figure 1 is a fragmentary view in side elevation, showing my device attached to one car of a train; Fig. 2 is a vertical section on the line 2—2 of Fig. 1; and Fig. 3 is a longitudinal vertical section through the controlling valve.

Referring more particularly to the separate parts of the device, 1 indicates a car, which is supported in the usual manner by a truck 2 having wheels 3. On this car is provided any usual air-brake system, indicated at 4, which has a train pipe 5.

Located at any suitable point on the train pipe, and if desired, on each of the cars, there is provided a suitable controlling valve 6, which is adapted to connect the interior of the train pipe 5 with the atmosphere, so that the air pressure therein can be let out into the atmosphere. This valve may be of any desired structure, and as seen by refer-

ence to Fig. 3, may consist of a union 7 having a valve proper 8 with an opening 9 therein. The opening 9 is adapted to be brought into alignment with the openings 60 through the union and the train pipe 5, and is also adapted to connect the interior of the train pipe with an outlet 10. For the purpose of operating the valve 8, it is provided with an arm or lever 11, which has 65 adjustably secured thereto adjacent its outer end a weight 12, by any suitable means, such as a set screw 13. The arm 11 extends through a bracket 14, which is secured to the car in any well known manner, as by being bolted to the train pipe 5. The arm 11 is held in its normal raised position corresponding to the position in which the outlet 10 is closed by the valve 8, by means of a suitable projection 15, extending inwardly 70 from the side of the bracket and preferably rounded in form so as to readily release the arm 11. The arm 11 is held in intimate contact with the projection 15 and further supported by means of a suitable spring 16, 75 which is secured in any well known manner to the bracket 14. The spring 16 and the projection 15 will hold the lever 11 in its raised position, and thus the valve 8 in the position in which the outlet is closed under 80 all normal conditions. If, however, the wheels should leave the track or should break, the jolt of the fall of the car and the further jolt of the car in running over the ties would cause the weight 12 to force 90 the lever down between the spring 16 and the projection 15, thus opening the outlet 10 and permitting the pressure in the pipe 5 to go out into the atmosphere, thus setting 95 the brakes throughout the train almost instantaneously.

For the purpose of locking the lever 11 in its lowered position, and thus the valve 8 in its open position, so that the brakes will not be set and released by the constant jar-ring back and forth of the lever, the bracket 14 is provided with a suitable rack or ratchet 17, which will engage the lever and prevent its upward movement.

The adjustment of the weight 12 permits 105 the force which the spring 16 has to resist to be varied according to the conditions desired, so that the device may be made more or less sensitive.

It will thus be seen that a simple and efficient device is provided for automatically setting the brakes in case of an accident to 110

the car or trucks, of which the engineer can have no possible knowledge.

While I have shown one embodiment of my invention, I do not wish to be limited to the specific details thereof, but desire to be protected in various changes, modifications and alterations which I may make within the scope of the appended claims.

Having thus described my invention, I claim as new and desire to secure by Letters Patent:

1. The combination with a pneumatic brake system having a train pipe, of a valve for reducing the pressure in said train pipe, an arm for operating said valve, means for normally holding said arm stationary, and means actuated by an abnormal jar for overcoming said first-mentioned means and operating said arm.
  2. The combination with a brake system, of a valve for controlling the pressure in said system, an arm for operating said valve, a spring adapted to hold said arm stationary under normal jars, and means for actuating said arm to escape said spring when said arm is subjected to abnormal jars.
  3. The combination with a brake system having a train pipe, of a valve for controlling the pressure in said train pipe, an arm for operating said valve, a bracket, a projection on said bracket adapted to engage said arm, means for coöperating with said projection, adapted to support said arm, and a weight on said arm adapted to be operated by an abnormal jar to force said arm by said projection and said means.
  4. The combination with a brake system having a train pipe, of a valve for controlling the pressure in said pipe, an arm operating by gravity for moving said valve to open position, and means for holding the arm in position to hold the valve in closed position and from which means the arm is adapted to be disengaged by an abnormal jar.
  5. The combination with a brake system having a train pipe of a valve for controlling the pressure in said pipe, an arm operating by gravity for moving said valve to
- open position, means for holding the arm in position to hold the valve in closed position and from which means the arm is adapted to be disengaged by an abnormal jar, and means for locking the arm in the position to which it moves when disengaged from its holding means.
6. The combination with a brake system having a train pipe, of a valve for controlling the pressure in said train pipe, an arm for operating said valve, a bracket, means for yieldingly holding said arm in a position corresponding to the closed position of said valve, means for locking said arm in a position corresponding to the open position of said valve, and a weight on said arm adapted to actuate said arm when subjected to abnormal jars.
7. The combination with a brake system having a train pipe, of a valve for controlling the pressure in said train pipe, an arm for operating said valve, a bracket, means for yieldingly holding said arm in a position corresponding to the closed position of said valve, means for locking said arm in a position corresponding to the open position of said valve, and adjustable means on said arm adapted to be actuated by abnormal jars and adapted to manipulate said arm.
8. The combination with a brake system having a train pipe, of a valve for controlling the pressure in said train pipe, a bracket, an arm for operating said valve, extending in juxtaposition to said bracket, a projection on said bracket for supporting said arm, a spring on said bracket adapted to coöperate with said projection to support said arm, an adjustable weight on said arm, and a rack on said bracket adapted to maintain said arm in a position corresponding to the open position of said valve.

In testimony whereof I have signed my name to this specification in the presence of two subscribing witnesses.

HUGH SINCLAIR BEATTIE.
